COMBINED HANDBAG AND SHOPPING BAG

Paula Michaels, Brooklyn, N. Y.

Application September 29, 1955, Serial No. 38,153

Term of patent 3½ years

(Cl. D87—3)

Fig. 1.

Fig. 2.

Fig. 3.

Fig. 4-

I claim:

The ornamental design for a combined handbag and shopping bag, substantially as shown.
